[57] CLAIM

The ornamental design for a vertical pinball-type game housing, substantially as shown and described.

DESCRIPTION

FIG. 1 is a top front perspective view of a vertical pinball-type game housing showing my new design.
FIG. 2 is a rear elevational view of the game shown in
FIG. 1;
FIG. 3 is a side elevational view showing the left side of the game shown in FIG. 1;
FIG. 4 is a bottom plan view of the game shown in FIG.
1.
